United States Patent Office.

ANDREW R. HARRIS, OF ST. LOUIS, MISSOURI.

Letters Patent No. 105,071, dated July 5, 1870.

IMPROVEMENT IN APPARATUS FOR SIGNALING THE DIRECTION OF MOTION OF MARINE-ENGINES.

The Schedule referred to in these Letters Patent and making part of the same.

To all whom it may concern:

Be it known that I, ANDREW R. HARRIS, of St. Louis, in the county of St. Louis and State of Missouri, have made a certain new and useful Improved Device for Indicating the Motion of Engines, &c.; and I do hereby declare that the following is a full and true description thereof, reference being had to the accompanying drawing and to the letters of reference marked thereon.

This invention has for its object the formation of an indicating device, to be operated by the driving-shaft of the engine used in steam-boats or other vessels, that shall indicate to the pilot, captain, or other proper officer of the same, the exact motion (usually termed "running ahead" or "backing" motions) of said engine; and

Said invention relates to certain levers, which, when put in action, shall operate the rod or rope attachments that govern the action of the indicating devices displayed in a suitable tablet or frame in the pilot-house or other parts of the vessel or boat, as described.

To enable those skilled in the art to make and use my said invention, I will now more fully describe the same, referring to the accompanying—

Figure 1 as a sectional elevation; to

Figure 2 as a front elevation; and to

Figure 3 as a top plan.

On the driving-shaft A of the engine, I place a suitable pinion, the teeth *a* whereof are at proper distances apart, and are made long.

Said pinion actuates the horizontal levers C and C'; these are pivoted, at *c*, in a suitable standard-frame.

Said levers C and C' again actuate the horizontal levers D D', pivoted at *d*.

The lever C, at its outer end, is halved, to underlie the lever D, and similarly the lever D' is halved to underlie the lever C'.

Each of said levers is held on either side by spring E, secured to the standard-frame.

It is plain, therefore, that, in a forward motion of the engine, the levers C and D will be active, while no motion will be transmitted to the lever D', and,

vice versa, the levers C' and D' will be active, in the backward motion, while the lever D remains stationary.

From the engine-room, in which said levers are arranged, as aforesaid, I connect the ends of the levers D D' by wires, rods, or rope, E, and suitable bell-crank lever attachments, in any proper manner, so as to operate a spiral spring, F, and indicator-knobs *f* and *f'*, arranged in a proper frame and tablet, F', in the pilot-house, or other parts of the vessel where it is deemed preferable to display said tablet.

For an initial adjustment of the parts for connection, a turn-buckle, with right and left threads, will be used, as indicated in the drawing, and a spiral or other spring may be inserted in the line of rope, to allow for any distortion of the vessel, or undue strain.

The tablet F' or indicating knobs may be suitably lettered or designated, to more clearly understand the movement of the parts, as desired.

When, therefore, the levers are operated by the engine-shaft, it is plain that, by the arrangement of the different parts, a reciprocating motion is imparted respectively to each indicating device, in accordance with the motion of the engine, and that my said device is practically effective in enabling the proper officer of the boat to understand the exact motion of the engine, and thus to guard against confusion and error, that often result in accidents and disasters.

Having thus fully described my said invention,

What I claim is—

1. The shaft A, arranged with pinion having teeth *a*, in combination with the levers C C', D D', substantially as and for the purpose set forth.

2. The levers C C', D D', in combination with the tablet F, arranged with spring F and indicating devices *f f'*, substantially as set forth.

In testimony of said invention I hereunto set my hand in presence of—

A. R. HARRIS.
